UNITED STATES PATENT OFFICE.

JOHN T. KLUGH, OF MADISON, MISSOURI.

INSULATOR.

971,619.

Specification of Letters Patent.

Patented Oct. 4, 1910.

Application filed August 3, 1909. Serial No. 511,041.

To all whom it may concern:

Be it known that I, JOHN T. KLUGH, citizen of the United States, residing at Madison, in the county of Monroe and State of 5 Missouri, have invented certain new and useful Improvements in Insulators, of which the following is a specification.

This invention relates to insulators and has for its object to provide a comparatively 10 simple and inexpensive device of this character especially designed for supporting the line wires on telegraph poles and the like.

A further object of the invention is to provide an insulator, the supporting pin of 15 which is provided with resilient clamping jaws adapted to embrace the major portions of the insulator sections, there being seating recesses formed in said sections for the reception of the clamping jaws so that the latter will be disposed flush with the interior surface of the insulator, and thus not offer any obstruction to the adjacent line wires.

A further object is to provide an insulator, 25 the mating sections of which may be removed from or inserted between the clamping jaws of the supporting pin from either the top or the opposite ends of the latter.

A still further object of the invention is 30 generally to improve this class of devices so as to increase their utility, durability and efficiency.

Further objects and advantages will appear in the following description, it being 35 understood that various changes in form, proportions and minor details of construction may be resorted to within the scope of the appended claims.

For a full understanding of the invention 40 and the merits thereof and also to acquire a knowledge of the details of construction and the means for effecting the result, reference is to be had to the following description and accompanying drawings, in which:

45 Figure 1 is a perspective view of an insulator constructed in accordance with my invention showing the same in position on the cross arm of a telegraph pole, a portion of the cross arm being broken away to expose the shank of the supporting pin; Fig. 50 2 is a vertical sectional view of the device detached from the supporting arm; Fig. 3 is a perspective view of the upper portion of the supporting pin, the insulator sections 55 being shown in position to be inserted between the clamping jaws and the securing

bolt and nut on opposite sides of said jaws; Fig. 4 is a transverse sectional view taken on the line 4—4 of Fig. 2.

Corresponding and like parts are referred 60 to in the following description and indicated in all the views of the drawings by the same reference characters.

The improved insulator forming the subject matter of the present invention comprises a longitudinally split supporting pin 5, preferably rectangular in shape as shown, and provided with a reduced threaded shank 6 adapted to be screwed or otherwise embedded in the cross arm 7 of a telegraph 70 pole. The upper ends of the resilient arms 8 of the supporting pin, are extended laterally to form concavo-convex clamping jaws 9 adapted to enter seating recesses 10 formed in the insulator sections 11. The insulator 75 sections 11 may be formed of glass, porcelain or other suitable material and are provided with longitudinally disposed seating grooves 12 arranged at the abutting faces of the insulator sections and having their 80 walls roughened or corrugated at 13 for engagement with the line wire 14.

Attention is here called to the fact that the seating recesses 10 terminate short of the top of the insulator and gradually decrease 85 in depth from the shoulders 15 to the bottom of the insulator so that when the clamping jaws 9 embrace the insulator sections 11, the outer faces of the jaws will be disposed flush with and form a continuation of the top wall 90 of the insulator, thus not to offer any obstruction to the adjacent line wires when the supporting pin is used on the cross arm of a telegraph pole.

As a means for clamping the jaws 9 in engagement with the insulator sections 11, the arms 8 thereof are provided with transversely aligned perforations 16 adapted to receive a bolt or similar fastening device 17, which latter extends through the perforations 16 for engagement with a clamping nut 18.

By making the groove 10 of gradually decreased depth from the top of the insulator to the bottom thereof, the sections 11 may be readily removed from the top of the supporting pin, the inherent resilient properties of the clamping jaws 9 permitting sufficient expansion of said jaws when the fastening device 17 is partially released to permit the ready withdrawal of the insulator sections. This gradual decrease of the

groove 10 also permits the terminals of the clamping jaws 9 to firmly grip the walls of the groove 10 with said terminals bearing against the shoulders 15, thus positively to 5 retain the insulator sections between the clamping jaws and securely hold the same in engagement with the line wire. It will here be noted that the opposite side walls of the recesses 10 are inclined or beveled at 19 so 10 that when the fastening device or bolt 17 is loosened, the insulator sections 11 may also be removed through the opposite ends of the clamping jaws, the inclined faces 19 permitting said sections to be readily withdrawn 15 from the clamping jaws.

Thus it will be seen that there is provided an insulator which when in position on the supporting pin will present a smooth and unobstructed exterior surface so that liability of the insulator catching on adjacent line wires is positively eliminated. 20

Having thus described the invention, what is claimed as new is:

1. A device of the class described including an insulator having a circumferential recess formed therein and gradually decreasing in depth from a point adjacent the top of the insulator to the bottom thereof, and a longitudinally split supporting pin having 25 means at one end thereof for engagement with a support and provided at its other end with clamping jaws adapted to enter the seating recess in the insulator, the exterior walls of the clamping jaws being devoid of 30

surface projections and disposed flush with 35 and forming a continuation of the exterior walls of the insulator at the top thereof and between the free ends of said jaws.

2. A device of the class described including an insulator having a longitudinally disposed wire receiving opening and provided with a circumferential seating recess defining oppositely disposed stop shoulders at the top of the insulator, said recess gradually decreasing in depth from the shoulders to 45 the bottom of the insulator and having its side walls beveled, a longitudinally split supporting pin having means at one end thereof for engagement with a support and having its other end provided with clamping 50 jaws adapted to enter the seating recess in the insulator and having their opposite edges beveled for engagement with the beveled walls of said seating recess, and a fastening device extending transversely through the 55 split portion of the pin for clamping the jaws in engagement with the insulator, the exterior walls of the clamping jaws being devoid of surface projections and disposed flush with and forming a continuation of 60 the top of the insulator between said stop shoulders.

In testimony whereof I affix my signature in presence of two witnesses.

JOHN T. KLUGH. [L. S.]
